[57] CLAIM

We claim the ornamental design for a tractor tire cleat cover, as shown and described.

DESCRIPTION

FIG. 1 is a perspective view of a tractor tire cleat cover showing our new design;

FIG. 2 is a top plan view thereof in a flat condition;

FIG. 3 is a bottom plan view thereof in a flat condition;

FIG. 4 is a front elevational view thereof in a flat condition;

the rear elevational view being a mirror image of this Figure;

FIG. 5 is a right end elevational view thereof; and,

FIG. 6 is a left end elevational view thereof.
